United States Patent

Des. 240,955

Patented Aug. 10, 1976

240,955

TOY TOOL BOX

Michael L. Satten, 245-28 Grand Central Parkway,
Bellrose, N.Y. 11362

Filed Jan. 23, 1975, Ser. No. 543,358

Term of patent 14 years

Int. Cl. D21—01

U.S. Cl. D34—15 R

FIG. 1

FIG. 2

FIG. 3

FIG. 4

FIG. 5

FIG. 1 is a top plan view of a toy tool box showing my new design;

FIG. 2 is a front elevational view thereof;

FIG. 3 is a rear elevational view thereof;

FIG. 4 is a bottom plan view thereof; and

FIG. 5 is a right side elevational view thereof.

I claim:

The ornamental design for a toy tool box, as shown.
